FIRING MECHANISMS FOR AUTOMATIC LOADING ARMS

Miguel E. Manzo Sal, Cordoba, Argentina

Application December 1, 1952, Serial No. 323,410

12 Claims. (Cl. 89—140)

This invention relates to an improved firing mechanism for automatic loading arms, such as submachine guns and the like firearms and more particularly it refers to a firing mechanism the number of parts of which is considerably smaller than those of at least most of the known firing mechanisms for similar type of arms. Still more specifically this invention relates to a trigger and sear sub-assembly.

It is to be understood that the improved firing mechanism of the present invention or more specifically the principle of operation on which said firing mechanism is based, may be adapted to a different number of fire arms such as submachine guns, machine pistols, both of the automatic and semi-automatic type as well as any other similar small arm.

It is an object of the invention to provide a new type of firing mechanism which is susceptible of economical mass production.

Another object of the invention is to provide a firing mechanism which will function in a reliable manner under all conditions of service.

It is still another object of the invention to provide a firing mechanism which by means of a selector may be used both as an automatic as well as a semi-automatic firing mechanism.

These and further objects and advantages of the present invention will become more apparent in the course of the following specific description, in which by way of example two specific embodiments are described.

In the drawings:

Figure 1 is a longitudinal vertical sectional view of one of the embodiments of the firing mechanism of the present invention.

Figure 2 is a partial, longitudinal, vertical sectional view of another embodiment of the firing mechanism based on the same principle.

Figures 3-6 are schematical longitudinal vertical sectional views, showing four of the main positions of the firing mechanism of Figure 1, when operating as a semi-automatic firing mechanism.

Figures 7 and 8 are schematical longitudinal vertical sectional views, showing two of the main positions of the firing mechanism of Figure 1, when operating as an automatic firing mechanism.

Figure 9 is a perspective view of the automatic sear of the firing mechanism of Figure 1 and in which the semi-automatic sear of the firing mechanism has been indicated in dotted lines.

Figure 10 is a detail in perspective view of the automatic sear of the firing mechanism shown in Figure 2.

As may be seen in Figure 1, only part of a firearm is shown and there is indicated an inertia block housing 1 which forms part of the bolt housing (not shown) and this housing 1 is provided with an inertia block 2 that is slidably housed therein and comprising at one end a spring guide projection 3 coaxial with the axis 4 of the inertia block 2. The opposite end of said inertia block 2 is provided with a bolt (not shown). The end of the

2

housing adjacent to the spring guide projection 3, is, as usually, provided with a cap (not shown) on which the bolt and inertia block driving spring 5 butts, against a platform 6.

5 The inertia block 2 is provided with a sear engaging shoulder 7 adapted to face an opening 8 of said housing 1 when said inertia block 2 is in its inoperative positions, as will be later explained. The sear engaging shoulder 7 forms part of a recess 9 in said inertia block 10 2, the opposite end 10 with regard to the sear engaging shoulders 7 is concavely shaped, so that during the backward movement of the inertia block 2 the heel, as will be later explained may be conveniently inserted.

The trigger and sear sub-assembly consists of a pivot 11 located outside of the housing 1 and supporting a semi-automatic sear 12 housed in an at least partially hollow automatic sear 13 having a trigger 14, as may be also seen in Figure 9.

The semi-automatic sear 12 comprises at one end a first heel 15 adapted to engage said sear engaging shoulder 7 and at the opposite end, that is to say on the other side of pivot 11, which operates as a fulcrum, a first spring housing or casing 16 in which a first compression spring 17 is partially housed having a first end 17' butting 20 against the base portion 16' of said housing 16 and a second end portion 17'' butting against a base 18' of a spring guide 18. Said base 18' is suitably fixed to the outer face of said housing 1.

The heel 15 comprises a flat surface 15' which is substantially parallel with the sear engaging shoulder 7, when the semi-automatic sear 12 is engaging said shoulder 7. The base portion 12' of the semi-automatic sear 12 is provided with a cylinder 19 having a piston 20 elastically urged by spring 21 which is suitably housed 25 in said cylinder 19. One end 21' of said spring 21 butting against the base 19' of said cylinder 19 whilst the other end 21'' of said spring 21 is suitably guided by a spring guide 22 of said piston 20. A stop 23 integral with said cylinder 19 limits the forward and backward 30 movements of said piston 20 which has a recess 24 in which said stop 23 is housed. The head 20' of said piston 20 emerges out of said cylinder and is adapted to engage the automatic sear 13 in a recess 25 forming part of a friction surface 26.

The automatic sear 13 comprises in this embodiment of 45 Figure 1 a second heel 27 which has a flat surface 27' of similar inclination as said flat surface 15' of the semi-automatic sear 12. The automatic sear 13 is also provided with a second spring housing or casing 28 located behind the trigger 14 and at the opposite end with regard to pivot 11 in comparison with heel 27 in a similar way as the first spring housing 16. A second spring guide 29 having a base 29' operates in connection with a second compression spring 30 in a similar way as the first compression spring 17.

55 Finally a selector 31 swingably and controllably mounted on a shaft 32 supported by the automatic sear 13 and accessible from outside, enables to control the semi-automatic sear 12 so that the trigger 14 and sear mechanism may operate as a semi-automatic or automatic unit as will be later explained.

When the selector 31 is in its inoperative position, as shown in Figures 1 and 3 to 6, the trigger and sear mechanism operates as a semi-automatic unit. By "semi-automatic unit" is to be understood an assembly which fires one shot upon each operation of the trigger 14; while an "automatic unit" is a mechanism which continuously fires, while the trigger is pressed and as long as the supply holds.

70 The operation of the firing mechanism when operating as a semi-automatic unit is clearly shown in Figures 3-6, and is as follows:

The inertia block 2 is in its inoperative position, that is to say it is locked by heel 15 of the semi-automatic sear 12, as shown in Figure 3, wherein said inertia block and more particularly the sear engaging shoulder 7 thereof is facing the opening 8 of the inertia block housing 1. Piston 20 engages the recess 25 of friction surface 26 and thereby the automatic sear 13 is coupled to the semi-automatic sear 12. The arrangement of piston 20, and cylinder 19 with its accessories will be simply called "elastic engaging means" 34.

In the inoperative position of inertia block 2 the bolt and inertia block driving spring 5 is compressed so that upon releasing said block 2, said spring 5 will drive said block 2 in the direction shown by arrow 33 in Figure 4. In other words upon pressing trigger 14, the coupled assembly of the automatic sear 13 and semi-automatic sear 12 will rotate about pivot 11 and since the elastic engaging means 34 is coupling the semi-automatic sear to the automatic sear, both heels 15 and 27 will withdraw from recess 9 whereby the sear engaging shoulder 7 is freed and the block 2 moves forward in the direction shown by arrow 33 as can be clearly appreciated in Figure 5. At the same time the first spring 17 and second spring 30 are starting to be compressed and while the movement of trigger 14 continues in the direction shown by arrow 35, a position will be reached in which said first spring 17 is fully compressed whereby a further rotation about pivot 11 of the semi-automatic sear 12 is stopped, while the second spring 30 of the automatic sear 13 is still not totally compressed, so that a further rotation about pivot 11 of the automatic sear 13 is still possible. Upon further rotating the automatic sear 13 (see Figure 6), the elastic engaging means 34 and more particularly piston 20 disengages recess 25 and thereby disconnects the semi-automatic sear 12 from the automatic sear 13 and the first spring 17 immediately exerts an active pressure on base 16' of housing 16 returning the semi-automatic sear 12 to its inoperative position. While these several steps are performed, the bolt of inertia block 2 has fired and the gases have forced back, in the direction shown by arrow 36, the inertia block 2 against the opposition of the driving spring 5 so that the first spring 17 will force to engage the flat surface 15' of heel 15 with the sear engaging shoulder 7, and thus the firing operation is stopped. As shown in Figure 6, the recess 9 is sufficiently long to allow the insertion of heel 15 even if during the backward movement of block 2 the latter is further back than necessary for the engagement of flat surface 15' with shoulder 7. Upon releasing trigger 14, the automatic sear 13 returns to its inoperative position by the action of compressed second spring 30 and piston 20 again engages recess 25 so that the assembly adopts again the position as shown in Figure 3.

Repetition of the steps as above explained, will produce the firing of another shot.

It can thus be understood that the operation of the device is based on the principle of providing an automatic sear and a semi-automatic sear which may be temporarily coupled by means of the elastic engaging means 34 and which automatic and semi-automatic sears have different moments of rotation so that the semi-automatic sear will be uncoupled from the automatic sear before the latter has accomplished its actuating movement. By "actuating movement" is to be understood the movement as shown by arrow 35, that is to say when the trigger is pressed by the firer.

If the firing mechanism is to be used in automatic operation, that is to say "continuous or automatic firing," shaft 32 has to be operated from outside so that the selector 31, as shown in Figures 7 and 8 will constantly maintain withdrawn the semi-automatic sear 12 and more particularly the first heel 15 from the recess 9 and more particularly from the sear engaging shoulder 7. Upon operating trigger 14 that is to say, upon withdrawing the second heel 27 from recess 9, as shown in Figure 8, the

inertia block 2 is free to continuously operate whilst the trigger 14 and thereby the second heel 27, is maintained in its operative position in which position piston 20 preferably engages recess 25 so that the tensile force exerted by second spring 30 on trigger 14 is decreased. However the tensile force of second spring 30 is sufficient to overcome the tensile force of spring 21 (see Figure 1) upon releasing trigger 14 and thereby the inertia block 2 is stopped, because the second heel 27 enters through opening 8 to engage the sear engaging shoulder 7.

It will be apparent to those skilled in the art that the same result could be obtained if the elastic engaging means 34 would be integral with the automatic sear 13 and the recess 25 and friction surface 26 would be provided by the semi-automatic sear 12.

In order to demonstrate that the principle of the firing mechanism as explained above, may be applied to other embodiments, a further embodiment has been shown in Figure 2, wherein there is provided an inertia block housing 101, an inertia block 102, a spring guide projection 103, an axis 104, a bolt and inertia block driving spring 105, a platform 106, a sear engaging shoulder 107, an opening 108, a recess 109 having a concave opposite end 110. The trigger and sear sub-assembly consists of a pivot 111, a semi-automatic sear 112, an automatic sear 113 having a trigger 114, a heel 115 having a flat surface 115' for engaging the sear engaging shoulder 107. A first spring housing 116 and a first compression spring 117 and a spring guide 118; a cylinder 119 and a piston 120, a spring 121 for urging said piston 120 and a spring guide 122, a stop 123 and a recess 124, a second spring housing 128, a second spring guide 129 and a second compression spring 130. Said piston 120 and accessories form an assembly hereinafter called the "elastic engaging means" 134.

All the above elements operate in exactly the same manner as described in connection with the other embodiment shown in Figure 1. The main difference is that this embodiment shown in Figure 2 is preferably used for small arms and to this end the automatic sear 113 is simply a trigger 114 having two jaws or side plate members 137 and 138 (see also Figure 10) between which the semi-automatic sear 112 is housed and both the automatic sear 113 and the semi-automatic sear 112 are swingably mounted on pivot 111. A transverse friction bar 139 is the substitute for the friction surface 26 of the embodiment shown in Figure 1.

The operation of the device when operating as a semi-automatic device is exactly the same as that of the embodiment shown in Figure 1 and will therefore not be described again.

If this device is to be operated as an automatic device, then stop 123, which is a slidable stop, can be displaced towards the opposite end of recess 124 with regard to the position shown in Figure 2, whereby piston 120 is not able to penetrate into cylinder 119 and thus the semi-automatic sear 112 is constantly coupled to the automatic sear 113 and as long as the trigger 114 is operated, or depressed, the firing arm will operate as an automatic device or as a "machine gun."

It is obvious that although in the above description reference has only been made to an inertia block, that the latter can be replaced by any suitable mechanism as, for example, a slidable percussion hammer.

Although reference is mainly made to small arms, it is obvious that the firing mechanism of the present invention may be applied to any type of automatic-loading arms.

I claim:

1. A firing mechanism for automatic-loading arms such as sub-machine guns and the like firearms, comprising an inertia block housing having an opening, an inertia block slidably housed in said housing and having a sear engaging shoulder adapted to face said opening in its inoperative position, a semi-automatic sear and an automatic sear having trigger means for operating said firing

mechanism, a pivot outside said housing and pivotally supporting said semi-automatic sear and said automatic sear, said semi-automatic sear having a first end and a second end opposite said pivot, said semi-automatic sear having a heel for engaging said sear engaging shoulder through said opening, said heel being located at said first end, elastic engaging means supported by one of said sears for temporarily coupling said semi-automatic and automatic sears, first spring means for said automatic sear in opposite working relationship with regard to said trigger means, and second spring means for said semi-automatic sear located at said second end, for engaging said heel with said sear engaging shoulder, and means for driving said inertia block, said first spring means being arranged so that it will be fully compressed before said second spring means upon operation of said trigger means to thereby block the pivotal movement of said semi-automatic sear with respect to said automatic sear.

2. A firing mechanism for automatic loading arms such as sub-machine guns and the like firearms, comprising an inertia block housing having an opening, an inertia block slidably housed in said housing and having a single sear engaging shoulder adapted to face said opening in its inoperative position, a pivoted semi-automatic sear and a pivoted automatic sear, located at least partially outside said housing, said semi-automatic sear having a heel for engaging said sear engaging shoulder through said opening, engaging means supported by said semi-automatic sear and for engaging said automatic sear, said automatic sear having trigger means for operating said firing mechanism, first spring means for said semi-automatic sear for engaging said heel with said sear engaging shoulder, and second spring means for said automatic sear in opposite working relationship with regard to said trigger means, and means for driving said inertia block, said first spring means being arranged so that it will be fully compressed before said second spring means upon operation of said trigger means to thereby block the pivotal movement of said semi-automatic sear with respect to said automatic sear.

3. A firing mechanism for automatic loading arms such as sub-machine guns and the like firearms, comprising an inertia block housing having an opening, an inertia block slidably housed in said housing and having a sear engaging shoulder adapted to face said opening in its inoperative position, a pivot, a semi-automatic sear and an automatic sear each mounted on said pivot and located at least partially outside said housing, said semi-automatic sear having a heel for engaging said sear engaging shoulder through said opening, engaging means, said semi-automatic sear supporting said engaging means for engaging said automatic sear, said automatic sear having trigger means for operating said firing mechanism, first spring means for said semi-automatic sear for engaging said heel with said sear engaging shoulder, and second spring means for said automatic sear in opposite working relationship with regard to said trigger means, and means for driving said inertia block, said first spring means being arranged so that it will be fully compressed before said second spring means upon operation of said trigger means to thereby block the pivotal movement of said semi-automatic sear with respect to said automatic sear.

4. A firing mechanism for automatic loading arms such as sub-machine guns and the like firearms, comprising an inertia block housing having an opening an inertia block slidably housed in said housing and having a sear engaging shoulder adapted to face said opening in its inoperative position, a pivot, a semi-automatic sear and an automatic sear each mounted on said pivot and located at least partially outside said housing, said automatic sear being at least partially hollow and said semi-automatic sear being at least partially housed in said automatic sear, said semi-automatic sear having a heel for engaging said sear engaging shoulder through said

opening, engaging means, said semi-automatic sear supporting said engaging means for engaging said automatic sear, said automatic sear having trigger means for operating said firing mechanism, first spring means for said semi-automatic sear for engaging said heel with said sear engaging shoulder, and second spring means for said automatic sear in opposite working relationship with regard to said trigger means, and means for driving said inertia block, said first spring means being arranged so that it will be fully compressed before said second spring means upon operation of said trigger means to thereby block the pivotal movement of said semi-automatic sear with respect to said automatic sear.

5. A firing mechanism for automatic loading arms such as sub-machine guns and the like firearms, comprising an inertia block housing having an opening an inertia block slidably housed in said housing and having a sear engaging shoulder adapted to face said opening in its inoperative position, a pivot, a semi-automatic sear and an automatic sear each mounted on said pivot and located at least partially outside said housing, said semi-automatic sear having a heel for engaging said sear engaging shoulder through said opening, elastic engaging means comprising a cylinder integral with said semi-automatic sear, a spring housed in said cylinder, a piston partially housed in said cylinder and resiliently urged outwardly by said spring, said piston having a head emerging out of said cylinder for engaging said automatic sear, said automatic sear having trigger means for operating said firing mechanism, first spring means for said semi-automatic sear for engaging said heel with said sear engaging shoulder, and second spring means for said automatic sear in opposite working relationship with regard to said trigger means, and means for driving said inertia block, said first spring means being arranged so that it will be fully compressed before said second spring means upon operation of said trigger means to thereby block the pivotal movement of said semi-automatic sear with respect to said automatic sear.

40 6. A firing mechanism as claimed in claim 5, wherein said cylinder being provided with a stop, said piston is provided with a recess in which said stop is housed.

7. A firing mechanism for automatic loading arms such as sub-machine guns and the like firearms, comprising an inertia block housing an opening having an inertia block slidably housed in said housing and having a sear engaging shoulder adapted to face said opening in its inoperative position, a pivot, a semi-automatic sear and an automatic sear each mounted on said pivot and located at least partially outside said housing, said semi-automatic sear having a heel for engaging said sear engaging shoulder through said opening, elastic engaging means comprising a cylinder integral with said semi-automatic sear, a spring housed in said cylinder, a piston partially housed in said cylinder and resiliently urged outwardly by said spring, said piston having a head emerging out of said cylinder, a friction surface having a recess forming part of said semi-automatic sear said friction surface and recess being located in front of said head of said piston, said head being capable of engaging said recess, said automatic sear having trigger means for operating said firing mechanism, first spring means for said semi-automatic sear for engaging said heel with said sear engaging shoulder, second spring means for said automatic sear in opposite working relationship with regard to said trigger means, and means for driving said inertia block, said first spring means being arranged so that it will be fully compressed before said second spring means upon operation of said trigger means to thereby block the pivotal movement of said semi-automatic sear with respect to said automatic sear.

8. A firing mechanism for automatic loading arms such as sub-machine guns and the like firearms, comprising an inertia block housing having an opening an inertia block slidably housed in said housing and having a sear en-

gaging shoulder adapted to face said opening in its inoperative position, a pivot, a semi-automatic sear and an automatic sear each mounted on said pivot and located at least partially outside said housing, said semi-automatic sear having a heel for engaging said sear engaging shoulder through said opening, said automatic sear having trigger means for operating said firing mechanism, first spring means for said semi-automatic sear for engaging said heel with said sear engaging shoulder, and second spring means for said automatic sear in opposite working relationship with regard to said trigger means, said automatic sear comprises two separated side plate members, a transverse friction bar linking said two separated side plate members, said semi-automatic sear being partially housed between said two side plate members, elastic engaging means, said semiautomatic sear supporting said elastic engaging means for engaging said transverse friction bar of said automatic sear, and means for driving said inertia block, said first spring means being arranged so that it will be fully compressed before said second spring means upon operation of said trigger means to thereby block the pivotal movement of said semi-automatic sear with respect to said automatic sear.

9. A firing mechanism for automatic loading arms such as sub-machine guns and the like firearms, comprising an inertia block housing having an opening an inertia block slidably housed in said housing and having a sear engaging shoulder adapted to face said opening in its inoperative position, a pivot, a semi-automatic sear and an automatic sear each mounted on said pivot and located at least partially outside said housing, said semi-automatic sear having a heel for engaging said sear engaging shoulder through said opening, said semi-automatic sear being provided with engaging means for engaging said automatic sear, said automatic sear having trigger means for operating said firing mechanism, said automatic sear comprises two separated side plate members, a transverse bar linking said two separated side plate members, said semi-automatic sear being partially housed between said two side plate members, elastic engaging means, said semi-automatic sear supporting said elastic engaging means for engaging said transverse friction bar of said automatic sear, first spring means for said semi-automatic sear, second spring means for said automatic sear, said second spring means comprising a second spring housing linked to said automatic sear and located behind said trigger means with regard to said pivot, a second compression spring partially housed in said second spring housing, a second spring guide integral with said inertia block housing and guiding said second compression spring, said first spring means comprising a first spring housing linked to said semi-automatic sear and located behind said trigger means and behind said second spring housing with regard to said pivot, a first compression spring partially housed in said first spring housing, a first spring guide integral with said inertia block housing and guiding said first compression spring, said first compression being so located and of such a length that it will be totally compressed before said second compression spring thereby limiting the pivotal movement of said semi-automatic sear in one direction with respect to said automatic sear, and means for driving said inertia block.

10. In a firing mechanism for automatic loading arms, a housing, an inertia block slidably mounted in said housing, a guide extending from an end of said block, a coil spring positioned in said housing and superimposed on said guide, said housing being provided with an opening therein, said block having a recess including a concave portion and a shoulder registering with the opening in said housing, a pivot pin positioned exteriorly of said housing, a semi-automatic sear supported by said pivot pin, a hollow automatic sear surrounding said semi-automatic sear and including a trigger, said semi-automatic sear including a heel adapted to engage said shoulder, and a casing, a coil spring positioned in said casing, a spring

guide secured to said housing and projecting into said coil spring, said heel including a flat surface extending substantially parallel to said shoulder when said semi-automatic sear engages said shoulder, said semi-automatic sear including a cylinder, a piston slidably mounted in said cylinder, a spring positioned in said cylinder and abutting said piston, there being a recess in said piston, a stop member projecting into said recess for limiting movement of said piston, said piston including an outer head engaging said automatic sear, said automatic sear including a second heel having a flat surface substantially parallel to the flat surface on said first heel, a casing on said automatic sear, a coil spring projecting into said last named casing, a spring guide secured to said housing and projecting into said last named spring, and a selector for controlling said semi-automatic sear.

11. In a firing mechanism for automatic loading arms, a housing, a hammer means slidably mounted in said housing, a guide extending from an end of said hammer means, a coil spring positioned in said housing and superimposed on said guide, said housing being provided with an opening therein, said hammer means having a recess including a concave portion and a shoulder registering with the opening in said housing, a pivot pin positioned exteriorly of said housing, a semi-automatic sear supported by said pivot pin, a hollow automatic sear surrounding said semi-automatic sear and including a trigger, said semi-automatic sear including a heel adapted to engage said shoulder, and a casing, a coil spring positioned in said casing, a spring guide secured to said housing and projecting into said coil spring, said heel including a flat surface extending substantially parallel to said shoulder when said semi-automatic sear engages said shoulder, said semi-automatic sear including a cylinder, a piston slidably mounted in said cylinder, a spring positioned in said cylinder and abutting said piston, there being a recess in said piston, a stop member projecting into said recess for limiting movement of said piston, said piston including an outer head engaging said automatic sear, said automatic sear including a second heel having a flat surface substantially parallel to the flat surface on said first heel, a casing on said automatic sear, a coil spring projecting into said last named casing, a spring guide secured to said housing and projecting into said last named spring, and a selector for controlling said semi-automatic sear.

12. A firing mechanism for automatic loading arms such as sub-machine guns and like fire arms, comprising an inertia block housing having an opening and an inertia block slidably housed in said housing and having a sear engaging shoulder adapted to face said opening in its inoperative position, a pivot, a semi-automatic sear and an automatic sear, each mounted on said pivot and located at least partially outside said housing, said semi-automatic sear having a heel for engaging said sear engaging shoulder through said opening, elastic engaging means comprising a cylinder integral with said semi-automatic sear, a spring housed in said cylinder, a piston partially housed in said cylinder and resiliently urged outwardly by said spring, said piston having a head emerging out of said cylinder for engaging said automatic sear, said automatic sear having trigger means for operating said firing mechanism, first spring means for said semi-automatic sear for engaging said heel with said sear engaging shoulder, and second spring means for said automatic sear in opposite working relationship with regard to said trigger means, and means for driving said inertia block, said first spring means being arranged so that it will be fully compressed before said second spring means upon operation of said trigger means to thereby block the pivotal movement of said semi-automatic sear with respect to said automatic sear, said cylinder being provided with a stop, said piston being provided with a recess in which said stop is housed, and said stop being integral with said cylinder.
